(57) **CLAIM**

The ornamental design for a one bottle tote apparatus, as shown and described.

DESCRIPTION

The present invention is a design for a product enabling bottle transport.

FIG. 1 is a front elevational view of a one bottle tote apparatus showing our new design;

FIG. 2 is a rear elevational view thereof;

FIG. 3 is a top plan view thereof;

FIG. 4 is a bottom plan view thereof;

FIG. 5 is a right side elevational view thereof, the left side elevational view being identical;

FIG. 6 is a perspective view thereof with a bottle inserted;

FIG. 7 is a front elevational view thereof;

FIG. 8 is a top plan view thereof;

FIG. 9 is a bottom plan view thereof; and,

FIG. 10 is a right side elevational view thereof, the left side elevational view being identical.

The broken line showing of stitching is for illustrative purposes only and forms no part of the claimed design.
